SPOOL TRANSFER DEVICE FOR WINDING MACHINES

Walter Siegenthaler, Erlenbach, Zurich, Switzerland, assignor to Maschinenfabrik Schärer, Erlenbach, Zurich, Switzerland

Application November 22, 1941, Serial No. 420,114
In Germany November 14, 1940

6 Claims. (Cl. 242—41)

This invention relates to spool transfer devices for winding machines.

The spool transfer device for winding machines, according to the invention, comprises a reciprocatory slide carrying a clamping mechanism which mechanism automatically cooperates with the spool, when the slide travels in one direction of movement, for the purpose of removing said spool out of position of mounting by moving the spool together with it, and which is rendered inoperative, when the slide travels in the opposite direction of movement.

By this means it is ensured that the completely wound spools are transferred in a relatively simple manner even if the diameter of the winding should vary. The spool transfer device, according to the invention, is applicable with particular advantage to winding machines having a plurality of spindles that are arranged on a common rotatable mounting member without, however, being restricted to this use.

An embodiment of the invention is illustrated in the accompanying drawing, by way of example only, in which

Fig. 1 shows an elevation of a winding machine including a slide, according to the invention, the slide being in position of rest;

Fig. 2 is a front elevation of Fig. 1 partly in section;

Fig. 3 is a sectional view of a detail of Fig. 2, and

Fig. 4 is a top plan view of Fig. 1, partly in section.

In the drawing, the numeral 1 designates the machine casing carrying exteriorly thereof a disc 3 which is rotatably mounted on an axle 2 projecting out of the casing and is provided with a circumferential rim. On the disc 3 seven winding spindles 4 are mounted in a circular row, each one of these spindles being in working position, that is, position of winding, at a time. In this position, the individual spool is adapted to be coupled into driving engagement with a driving spindle which projects out of the machine casing 1 and is longitudinally displaceably arranged on the casing 1.

As shown in the drawing, that winding spindle is in position of winding on which the spool A indicated in Figs. 1 and 3 is mounted for being wound. On the completion of the winding on the winding spindle being in position of winding the rotatable mounting member constituted by the disc 3 is, advantageously, automatically fed by a step, with the aid of means not shown, from the machine casing in the direction of the arrow

indicated in Fig. 2, whereby the winding spindle next following in the row is moved into coaxial alignment with the driving spindle mentioned above and is then coupled to the latter. The uncoupling of the winding spindle having previously been in position of winding from the driving spindle and the subsequent operation of coupling the further winding spindle having arrived in winding position is, advantageously, effected automatically from the driving gear of the machine by accordingly shifting said driving spindle. The character B designates a completely wound spool having been moved out of position of winding, due to rotational advancement of the disc 3, as shown in Figs. 1 and 2.

The machine indicated in the drawing is assumed to be a cop winding machine in which the cop building operation is effected, in a known manner, by means of a thread guide cooperating with the front winding cone while being fed step by step along a carrier rod which is axially reciprocated from the driving gear of the machine. The outer ends of the winding carriers or spools mounted on the winding spindles are individually received by a counter holder 5 being formed by a bolt which is axially adjustable relative to a carrier piece 7 by means of a set screw 6, when the respective winding spindle is in winding position together with the associated spool.

30 The carrier piece 7 is slidably mounted on a guide bar 8 arranged on the casing 1 and is normally urged in the direction toward the machine casing 1 by a coil spring 9 surrounding said bar, for the purpose of forcing the counter holder 5 into bearing engagement with the spool to be wound. The end of the guide bar 8 remote from the casing 1 is received by the upper portion of a front member 10 the lower portion of which is secured to a bar 11 which also is arranged on the casing 1. The two bars 8 and 11 guide a slide 12 which is provided with an upper fixed projecting arm 13, extending parallel with the guide bar 8, and a lower portion of which carries an angular support 14, by means of a screw 15. The angular support 14 is adjustable in height by means of a slot (not shown) which may be provided in the angular support 14, or in the slide 12, and receives the screw 15. On the angular support 14 a stirrup 16 is held, by means of a bent off leg 17. This stirrup 16 is secured to the angular support 14 by means of a threaded shank of a bolt 18 which shank passes through the leg 17. The screw bolt 18 protrudes through slots in the parts 17 and 14 whereby it is possible to 40 adjust the stirrup 16 transversely of the slide 12.

A swingable spool gripper arm 20 is mounted on the screw bolt 18, the latter preventing the stirrup 16 and the bolt from turning relative to the angular support 14 by means of a square portion passing through the said slots. The arm 20 is acted upon by a torsion spring 21. The spring 21 tends to urge the arm 20 into engagement with the stirrup 16 which is provided with a recess 22 for receiving said arm and provides a fixed abutment.

Assuming a wound spool to be located between the downwardly extending end portion of stirrup 16 and the end of pivoted, spring pressed arm 20, the size of the winding is such that the arm cannot swing to its extreme limit under the influence of the spring 21. When the stirrup and arm are moved toward the left, the inertia and resistance of the wound spool exert a drag on arm 20 tending to swing it farther to the right and thus increase the clamping effect against the winding. When moving in the opposite direction, the opposite effect would result, the arm being swung to the left and the clamping effect relieved.

The slide 12 is engaged by an actuating rod 23 which is connected with a guide slot carrier arm 25 through a connecting link 24. This arm is fastened to a shaft 26 in order to automatically perform one revolution at a time, when the machine operates and the spool being in winding position is completely wound. The connecting link 24 is adjustable relative to the guide slot carrier arm 25 for the purpose of regulating the traverse of the slide 12.

When the slide 12 is advanced from its position of rest shown in Fig. 1 toward the front by the action of the shaft 26 on the completion of the winding on an individual spool, the projecting arm 13 of the slide meets with the carrier piece 7 which piece is thus displaced against the influence of the compression spring 9, so that the counter holder 5 releases the spool being in winding position at that time. Concomitantly with said releasing operation also the winding feeler is moved out of the embrace of this spool by the action of the slide 12 by which means the preliminaries for feeding the disc 3 in the corresponding direction of rotation by one step are completed.

After the disc 3 has been fed by one step, in consequence of which, the completely wound spool A was removed from the winding position in order to be moved to the spot, that is, the transfer position at which the spool B is shown to be positioned, the return movement of the slide 12 begins. In this way the stirrup 16 is displaced so as to overlie the winding of the full spool situated in spool transfer position, so that the stirrup grips behind the winding and the arm 20 wipes over the latter. On the termination of the return movement of the slide 12 the condition of the transfer device as shown in Fig. 4 is obtained, in which the completely wound spool, then being in spool transfer position, is clamped between the stirrup 16 and the arm 20 and is moved along by the clamping mechanism constituted by said two parts, while the slide 12 performs the next following traverse, thereby being pulled out of the mounting head of the respective winding spindle 4. The rotational feed movement of the disc 3 then begins followed by the return movement of the slide 12, and so forth.

The advance movement of the slide 12 is stopped abruptly when the latter has reached the end of its traverse, the spool of relatively great

weight being entrained by the clamping mechanism 16, 20 then having the tendency, due to inherent inertia, to keep on moving in the direction of travel, whereby said spool overcomes the comparatively small power of the torsion spring 21 and thus turns the clamping arm 20 in the corresponding direction, thereby counteracting the clamping effect produced by the parts 16 and 20, so that the spool individually further advances to a slight extent, thereby dropping out of the clamping mechanism. In Figs. 3 and 4 the clamping mechanism 16, 20 is shown to be in a condition ready for operation.

The pivot bolt 18 of the clamping arm 20 makes it possible to adjust the arm 20 and the stirrup 16 transversely of the slide 12 in simple fashion, dependent upon requirements, that is, in accordance with the thickness of winding to be effected.

In the present instance the winding feeler means of the winding machine is adapted to carry the thread guide. It will, however, be readily seen that the spool transfer device according to the invention is applicable also to winding machines, which are provided solely with a thread guide being fed step by step and are thus devoid of winding feeler means. Further, the winding machine may be devoid of a counter holder for the spool being in winding position. Again, there is no absolute necessity for the winding machine to possess a plurality of winding spindles that are mounted on a common rotatable mounting member. Moreover, the construction of the spring-influenced clamping mechanism for the transfer of the full spools may be varied, as desired, and concerning the term "spool" this term is intended to cover any suitable winding carrier means.

I claim:

1. In a spool transfer device for winding machines of the type described, a reciprocating slide, a clamping mechanism carried by said slide, and means influencing said clamping mechanism to automatically cooperate with the winding on a spool for removing said spool out of its mounting position in the machine, while said slide travels in one direction of movement, said clamping mechanism being ineffective to grip a spool while said slide travels in the opposite direction of movement.
2. In a spool transfer device for winding machines of the type having a plurality of winding spindles, a rotatable mounting member in common with said winding spindles, feed means for rotatively advancing said mounting member for successively moving said spindles into and out of a position of winding in the machine, the transfer device comprising, a reciprocating slide, a clamping mechanism carried by said slide and located at a position removed from the winding position of the spindles, and means controlling said clamping mechanism to automatically cooperate with the winding on a spool which has been moved out of said position of winding for removing said spool out of its mounting position on said mounting member, while said slide travels in one direction of movement, said clamping mechanism being ineffective to grip a spool while said slide travels in the opposite direction of movement.
3. In a spool transfer device for winding machines of the type described, a reciprocating slide, a clamping mechanism carried by said slide, a fixed abutment and a cooperative spring-influenced swingable spool gripper arm included in said mechanism, and spring means influencing

said clamping mechanism to automatically grasp a spool, by the winding thereon, between said abutment and said gripper arm, for removing said spool out of its mounting position in the machine, while said slide travels in one direction of movement, said clamping mechanism being ineffective to grasp a spool while said slide travels in the opposite direction of movement.

4. In a spool transfer device for winding machines of the type described, a reciprocatory slide, a clamping mechanism carried by said slide, a fixed abutment and a cooperative spring-influenced swingable spool gripper arm included in said mechanism, said abutment and the pivot axis of said gripper arm being relatively adjustable transversely of said slide, and means adapting said clamping mechanism to automatically grasp a spool, by the winding thereon, between said abutment and said gripper arm against said spring influence, for removing said spool out of its mounting position in the machine, while said slide travels in one direction of movement, said clamping mechanism being ineffective to grasp a spool while said slide travels in the opposite direction of movement.

5. In a spool transfer device for winding machines of the type described, a reciprocatory slide, a clamping mechanism associated with said slide, said clamping mechanism comprising a stirrup, providing a fixed abutment, and a cooperative spring-influenced swingable spool gripper arm; a supporting member on said slide carrying said stirrup and the pivot axis of said gripper arm so

as both to be adjustably fixed to said member transversely of said slide, and spring means influencing said clamping mechanism to automatically grasp a spool, by the winding thereon, between said stirrup and said gripper arm for removing said spool out of its mounting position in the machine while said slide travels in one direction of movement, said clamping mechanism being ineffective to grasp a spool while said slide travels in the opposite direction of movement.

6. In a spool transfer device for winding machines of the type described, a reciprocatory slide, a clamping mechanism associated with said slide, said clamping mechanism comprising a stirrup, providing a fixed abutment, and a cooperative spring-influenced swingable spool gripper arm included in said mechanism, a supporting member on said slide carrying said stirrup and the pivot axis of said gripper arm so as both are adjustably fixed to said member transversely of said slide, a pivot bolt for said gripper arm adjustably fixing said stirrup and said gripper arm commonly to said supporting member, and spring means influencing said clamping mechanism to automatically grasp a spool, by the winding thereon, between said stirrup and said gripper arm for removing said spool out of its mounting position in the machine while said slide travels in one direction of movement, said clamping mechanism being ineffective to grasp a spool while said slide travels in the opposite direction of movement.
